UNITED STATES PATENT OFFICE.

JOSEPH M. POWELL, OF ORESTES, INDIANA.

ROTARY ENGINE.

SPECIFICATION forming part of Letters Patent No. 769,183, dated September 6, 1904.

Application filed November 23, 1903. Serial No. 182,230. (No model.)

To all whom it may concern:

Be it known that I, JOSEPH M. POWELL, a citizen of the United States, residing at Orestes, in the county of Madison and State of Indiana, have invented certain new and useful Improvements in Rotary Engines, of which the following is a specification.

Referring to the accompanying drawings, which are made a part hereof, and on which similar reference characters indicate similar parts, Figure 1 is a side elevation of a rotary engine embodying my said invention; Fig. 2, a central vertical sectional view thereof as seen when looking in the direction indicated by the arrows from the dotted lines 2 2 in Figs. 3 and 4; Fig. 3, an end elevation; Fig. 4, a central vertical sectional view as seen from the dotted lines 4 4 in Figs. 1 and 2; Fig. 5, a detail horizontal sectional view, on an enlarged scale, through the valve and its governing mechanism as seen when looking downward from the dotted line 5 5 in Figs. 1 and 2; Fig. 6, a view similar to a portion of Fig. 2, but on an enlarged scale; Fig. 7, a view similar to a portion of Fig. 4, but on an enlarged scale; and Fig. 8, a detail sectional view, on a still further enlarged scale, at the point indicated by the dotted line 8 8 in Fig. 6.

The cylinder of my improved engine is composed of the head 21, which also preferably embodies a part of the rim, as is best shown in Fig. 2, the head 22, and an upper rim portion 23, which portions are suitably secured together, as by cap-bolts 24. Within suitable grooves in the internal faces of the heads 21 and 22 are the packing-strips 25 and 26, and these are held against the rotary piston either by means of suitable springs, as 27 and 28, or by the force of a small quantity of steam 40 which (by means of suitable channels formed in the structure, as shown in Fig. 2) is admitted to the space behind said packing-strips. A packing-strip 29 is also provided to bear upon the edge of the rotary piston and is mounted in a suitable recess formed to receive it in the adjacent portion of the member 23. This strip may also be held into contact with the piston by means of a suitable spring; as 30, or the force of a small quantity

of steam which may be admitted to the space 50 behind it.

The heads 21 and 22 have extensions 31 and 32 thereon, which form bearings for the main shaft 33 of the engine. Said shaft carries upon one end the fly-wheel 34 and upon the other end a sprocket-wheel or pulley 35, which through the sprocket-chain or belt 36 and the sprocket-wheel or pulley 37 drives the combined governor and valve-shaft 41. This shaft 41 is mounted in an upwardly-extending portion of the member 23, (which member also embodies the steam-chest, as will be presently described,) and said shaft revolves at the same speed as the main shaft. This combined governor and valve-shaft is hollow, 65 and its open inner end registers with the inner end of the steam-pipe 42. One side contains a V-shaped valve-opening which extends across the steam-inlet to the steam-chest. Two wedge-shaped valve members 43 and 44 are 70 arranged within this V-shaped opening and are thus adapted as they are moved longitudinally thereof to approach or recede from each other, and thus diminish or increase the available orifice through which the steam passes to 75 the steam-chest, a portion of which orifice is bounded by these valve members and the remainder of which is the port 45, leading downwardly therefrom to the steam-chest. By means of these wedge-shaped valve portions I 80 not only govern the amount of steam admitted to the steam-chest, but admit it to the engines at full boiler-pressure directly and cut it off quickly and at any desired point, and thus get the full benefit of expansion. Said wedge-shaped valve portions are connected, by means of links 47 and 48, to a longitudinally-movable rod 49, which passes through a stuffing-box 50 and at a point beyond said stuffing-box is provided with a cross-bar 51, which engages 85 with a collar 52, slidably, but not revolvably, mounted on the shaft 41, it being prevented from revolving said shaft by the spline 53. This collar has an annular groove 54 in its outer face, and the inner arms of bell-crank 90 levers 55 and 56 (forming part of the governor mechanism) enter said groove, and thus engage with said collar. These bell-crank le-

vers 55 and 56 are mounted, by means of pivots 57 and 58, on arms of a spider 59, rigidly mounted upon the shaft 41. Said bell-crank levers carry the governor-balls 61 and 62 upon 5 their free arms, and these balls are held toward each other by spring 63. In operation as the speed increases the balls will fly apart and draw the collar 51, and with it the rod 49, toward the end of the shaft 41, carrying the 10 wheel or pulley 37, and thus (through the links 47 and 48) move the wedge-shaped valve parts 43 and 44 toward the narrow end of the V-shaped slit in said shaft 41, thus reducing the size of the orifice. As the speed decreases 15 the springs 63 operate to draw the governor-balls 61 and 62 toward each other, moving the rod 49 in the opposite direction and causing the wedge-shaped valve parts 43 and 44 to move backwardly. A spring 65 is placed 20 within the hollow shaft 41 with its ends extending over the wedge-shaped valve parts 43 and 44 and is thus adapted to hold said wedge-shaped valve parts in position and cause them to separate as they are moved backward to 25 ward the wider end of the V-shaped slit in the side of the hollow shaft, and thus open the orifice through which the steam flows to the steam-chest.

The stuffing-box 50 is of peculiar formation. Within the hollow shaft 41 at an appropriate point a shoulder is formed against which the washer-like plate forming one end of this stuffing-box rests. The compressible material forming the center of the stuffing-box 30 is then placed against this plate, and a second plate is then slipped over the rod 49, forming the other head of the stuffing-box. The pressure of the steam within this hollow shaft against this second plate is sufficient to 40 keep the stuffing-box tight.

The steam-chest is cylindrical in form, and its outer wall is a part of the member 23 of the shell of the engine. Within the cylindrical opening is a tubular structure 71, through 45 which are formed suitable ports for the transmission of steam from the valve to the engine-cylinder. I prefer to make my improved engine so that it can be caused to run in either direction, and in doing this I provide three 50 such ports in the tubular structure 71. Two of these, 72 and 73, are in the form of annular grooves cut into the wall of said tubular structure and extending completely around it, while the third is in the form of a transverse 55 slit cut through the wall of said structure and affording an opening from the outside thereof into its hollow center. As best shown in Fig. 5, these ports are situated equidistant from each other. The annular ports are the live-steam 60 ports, and the other, which is situated midway between the two, is the exhaust-port. Within the part 23 are two other ports, 75 and 76, which are arranged to form a continuation of two of the three ports of the tubular valve 71.

65 In the arrangement shown the live steam is

shown as entering through the ports 72 and 73, and the exhaust-steam is shown as escaping through the ports 76 and 74 and thence out the exhaust-steam pipe 80. The tubular valve 71 may, however, be shifted in position, 70 as by means of the lever 77 and its rod 78, so that the exhaust-port 74 will be brought into registry with the port 76. When this is done, the direction of rotation of the engine is reversed, as the steam then enters the cylinder 75 through the ports 73 and 76, and the exhaust-steam escapes through the ports 75 and 74.

The piston of this engine consists of a plain circular disk 81, which is mounted on shaft 33, and a radially-movable wing 82, mounted in a corresponding slit extending in front the periphery of said disk toward the center. Said wing is held outwardly against the inner surface of the rim of the engine-cylinder by centrifugal force during the time the engine is 80 in operation, and this may be aided or caused to act more quickly either by a spring 83, seated in a suitable perforation formed for the purpose underneath said wing or by steam-pressure admitted behind said wing through a 85 small orifice leading into the space containing it. The space between the piston and the cylinder-walls constitutes an annular chamber, except that at the upper portion (near where the steam enters) the circular form of the outer 90 wall is sufficiently departed from to bring said wall and the periphery of the piston-disk into close relation, so that the packing-piece 29, mounted in the wall at this point, shall bear closely against the periphery of the disk. 95

Having thus fully described my said invention, what I claim as new, and desire to secure by Letters Patent, is—

1. The combination, in a rotary engine, of a cylinder having one side flattened with steam-ports formed in the wall one on each side of the middle of the flattened portion, a packing-strip mounted in said wall between said ports, other packing-strips mounted radially in the cylinder-walls to bear against the sides of the 105 disk forming the piston, said piston composed of a disk and a radially-disposed wing movable toward and from its axis, a tubular valve 110 situated in the steam-chest and containing two live-steam ports and one exhaust-port positioned equidistant from each other whereby by shifting the position of said valve the direction of rotation of the engine may be reversed, and a suitable valve for the admission 115 of steam to the steam-chest, substantially as 120 set forth.

2. The combination, in a rotary engine, of the three members 21 22 and 23 forming the cylinder, said member 21 forming one end and the greater portion of the sides, the member 22 forming the other end, and the member 23 forming the remainder of the cylinder side and embodying the steam-chest, substantially 125 as shown and described.

3. The combination, in a rotary engine, of 130

a cylinder having one side flattened with steam-
ports formed in the wall one on each side of
the middle of the flattened portion, a packing-
strip mounted in said wall between said ports,
5 other packing-strips mounted radially in the
cylinder-walls to bear against the sides of the
piston, and a suitable piston.

4. The combination, in a rotary engine, of
a cylinder having one side flattened with steam-
ports formed in the wall one on each side of
the middle of the flattened portion, a packing-
strip mounted in said wall between said ports,

other packing-strips mounted radially in the
cylinder-walls to bear against the sides of the
disk forming the piston, and said piston com-
posed of a disk and a radially-disposed wing
movable toward and from its axis.

In witness whereof I have hereunto set my
hand and seal, at Indianapolis, Indiana, this
21st day of November, A. D. 1903.

JOSEPH M. POWELL. [L. s.]
